UNITED STATES PATENT OFFICE

2,603,861

TWINE DISPENSER

Lawrence D. Bartlett, Hartford, Ky.

Application October 2, 1947, Serial No. 777,489

2 Claims. (Cl. 30—127)

1

The present invention relates to new and useful improvements in cord or twine dispensers and more particularly to means for severing the twine into predetermined measured lengths as the same is dispensed from a container.

An important object of the invention is to provide a twine dispenser including a pivoted cutter operated through the medium of a pulling force exerted on the end of the twine while withdrawing the same from a container to sever the twine after a predetermined length thereof has been removed.

A further object is to provide novel means for keeping the twine under tension during its withdrawing and cutting operation and to keep the free end of the twine from re-entering the container.

Another object is to provide a dispenser of this character including a container for holding a ball of twine having a lid and mounting the cutting mechanism under the lid out of contact with the ball to prevent interference with the free unwinding of the twine from the ball.

A still further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the twine container.

Figure 2 is a vertical sectional view thereof.

Figure 3 is a bottom plan view of the lid showing the cutting mechanism mounted thereon.

Figure 4 is a top plan view of the sheave and cutter actuating cam carried thereby.

Figure 5 is a sectional view taken on a line 5—5 of Figure 4.

Figure 6 is an enlarged sectional view of one of the twine tensioning devices taken on a line 6—6 of Figure 2.

Figure 7 is an enlarged fragmentary bottom plan view of the sheave looking in the direction of the section lines 7—7 of Figure 2, and

Figure 8 is an enlarged perspective view of the cutter and spirally curved inner end actuated by the cam.

A similar twine dispenser is shown in applicant's patent, No. 2,580,878, issued January 1, 1952.

Referring now to the drawings in detail, wherein for the purpose of illustration I have disclosed a preferred embodiment of my invention, the numeral 5 designates a cylindrical container for holding a ball of twine 6 and having a flat top lid 7 telescoping thereon.

The lid is formed with openings 8 and 9 at diametrically opposite sides of its top, the free end 10 of the twine being withdrawn through opening 8 and extended across the top of the lid and over the opening 9. A box-like shield 11 having an open inner end covers the opening 8 and a box-like shield 12 covers the opening 9 and is formed in its top with an opening 13 which extends downwardly in the side walls of the shield to form V-shaped notches 14 and in which the free end of the twine is seated. The opening 13 is closed by a hinged cover 15.

A stud 16 extends downwardly from the under-side of the lid 7 eccentrically thereof and is formed with a shoulder 17 against which a sheave 18 journaled on the stud is held by a resilient U-shaped locking key 19 to space the sheave from the underside of the lid. The sheave is formed with a V-shaped groove circumferentially thereof in which the twine is seated. The upper surface of the sheave is provided with an arcuate cam 20 fixed thereto, the axis of the cam being eccentric to the axis of the sheave.

30 A cutter rod designated generally at 21 includes a straight outer end portion 22 pivoted on a pin 23 extending downwardly from lid 7, and a spirally curved inner end portion 24 in which the cam 20 is arranged to travel during 35 rotation of the sheave. To the outer end of the straight portion 22 of the cutter is fixed a blade 25 which projects through opening 9 and works in the shield 12. A coil spring 31 connects the outer end of cutter 21 to the lid 7.

40 A pair of twine tensioning devices 26 and 27 are secured under the lid 7, said devices being of duplicate construction and the device 26 being positioned adjacent opening 8. Each tensioning device comprises a ring 28 through which the twine passes and is held against the ring by a ball 29 and coil spring 30. The twine passes from the ball 6 first through the tensioning device 27, then around sheave 18 and through tensioning device 26 before passing through opening 8, the tensioning devices being arranged coplanar with the sheave 18 to hold a free end portion of the twine, pulled off the ball 6, and looped around said sheave in friction gripping engagement with the sheave.

55 In the operation of the device the free end of the twine is pulled through notches 14 in shield

12 off the ball 6, out of the opening 8, across the top of lid 7, and across opening 9, the frictional engagement of the loop of the twine with the sheave rotating the sheave and causing cam 20 to ride within the spiral end 24 of cutter 21 in a direction to place the spring 31 under tension and as the cam passes beyond the free end of spiral lever 24 and releases the latter, the spring 31 quickly pulls the blade 25 across the twine to sever the same. Accordingly the repeated rotation of sheave 18 and actuation thereby of cam 20 and cutter 21 will cut the twine in predetermined measured lengths as the twine is withdrawn from the container. By having the openings 8, 9 at diametrically opposite sides of the lid 7 and pulling the twine out of the opening 8 and cut at the diametrically opposite opening 9, a free end of the twine of substantial length is left outside the container 5 after each cutting operation for convenient grasping to pull more twine off the ball 6.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. In a twine dispenser of the type having a container for a ball of twine; a lid for said container having a flat top and a pair of openings in said top at opposite sides thereof through one of which a free end portion of the twine is

adapted to be manually pulled off the ball across said top and other opening, a sheave rotatably mounted on the top of said lid in spaced subjacent relation thereto and parallel therewith and around which a loop of said end portion of the twine is adapted to be passed to be pulled off the sheave through said one opening, a pair of twine tensioning devices on said lid coplanar with said sheave for tensioning said loop into frictional engagement with said sheave to cause rotation of said sheave by pulling of said loop off the sheave, a cutter rod having a cutter blade fixed on one end, said rod being pivoted intermediate its ends on said top between the same and said sheave for swinging in opposite directions in a plane parallel with said top, said cutter blade being fixed on said end of the cutter rod so as to project through said other opening to sever said end portion upon swinging of said rod in one direction, a tension spring connected to said rod and lid to swing said rod in said one direction, and a cam fixed on said sheave between the same and said top for rotation by said sheave to engage the other end of said rod for swinging the rod in the other direction to tension said spring.

2. In a twine dispenser according to claim 1, said other end of said rod comprising a spiral portion, said cam rotating in and riding against said spiral portion to swing said rod.

LAWRENCE D. BARTLETT.
